UNITED STATES PATENT OFFICE.

WILLIAM H. SMITH, OF LOS ANGELES, CALIFORNIA, ASSIGNEE TO SMITH & MARSH INCORPORATED, OF LOS ANGELES, CALIFORNIA, A CORPORATION OF CALIFORNIA.

TYPE FOR PRINTING VERTICAL COLUMNS OF FIGURES.

1,201,517.

Specification of Letters Patent.

Patented Oct. 17, 1916.

Application filed October 2, 1915. Serial No. 53,711.

To all whom it may concern:

Be it known that I, WILLIAM H. SMITH, a citizen of the United States, residing at Los Angeles, in the county of Los Angeles and State of California, have invented a new and useful Type for Printing Vertical Columns of Figures, of which the following is a specification.

My invention relates to the art of printing. In that art as practised in a job printing house large numbers of ruled forms are produced. These forms are used by accountants, and others, and may be bound into pads or books, or used separately. In such forms it is quite common to number each successive line, or to number lines at regular intervals. The figures used are usually consecutive, and form a vertical column. It is also common practice in specifications, legal papers, and other printed matter to similarly number either every line, or lines, at definite intervals. As a consequence of the great amount of work which must be so numbered there is a great amount of time spent in almost every job printing house in setting up and distributing the type used in such vertical columns of figures.

The principal object of my invention is to greatly reduce the time so spent. In the production of ruled forms it is common practice to produce the ruled lines in a ruling machine having multiple pens spaced accurately on the point system under which type is constructed. In the ordinary methods of setting up type for printing vertical columns of figures a large number of small pieces are necessarily used, and it is difficult and expensive to get an accurate alignment with the previously ruled lines. It is a further object of my invention to provide means for producing such an alignment.

My invention contemplates the use of movable type which is set up in the desired order with suitable spacers. When once so set up the assembly is tied up with string and handled as a unit. The printer therefore sets up certain commonly needed vertical columns of figures and ties the type up. The unit so produced he transfers in and out of his forms as desired, so that one set-up only is necessary. The type members used are of such a form that they can be readily tied up, and when so tied the string used for tying them is located in grooves entirely below the sides and ends of the type

assembly, so that the assembled unit will readily lock up with the furniture, or with any other type that may be used.

Further objects and advantages will be made evident hereinafter.

Referring to the drawings which illustrate several forms of my invention: Figure 1 represents an assembled unit using one form of type member. Figs. 2, 3, and 4 illustrate alternate forms of type member which may be used in assemblies similar to that shown in Fig. 1. Fig. 5 represents the same type as assembled with the inclusion of suitable spacing members. Fig. 6 represents the type members used in the assembly shown in Fig. 5. Fig. 7 illustrates an example of a ruled form having a vertical column of figures printed thereon such as is the object of the invention to produce.

In the form of the invention shown in these drawings it is desired to produce a ruled form such as that shown at 11 in Fig. 7. Ruled on this form are a series of lines 12, these lines being equally distant from each other, and being preferably ruled by multiple ruling pens. By the use of multiple ruling pens the distance between these lines is very accurately spaced according to the point system under which standard type is now made. In the production of ruled forms it is very common to number the lines by means of a vertical column of figures 13, these figures being in consecutive order, and being located preferably in the position 90 shown. It is also extremely common to so number alternate lines, or lines at definite intervals, and it is also common to number the lines on a printed page in the case of legal documents, engineering specifications, and the like. My invention is especially designed to produce such forms accurately and economically.

My invention consists essentially in providing movable type members such as those shown in the drawings in which a body 20 is provided having a face character 21 formed thereon. Side string grooves 22 are provided on either side of the body, and the vertical axis of the face character is arranged 105 parallel to these sides. A separate font of type is provided for each size of face character 21. In a job printing office, however, only a few sizes of face characters are necessary to suit all the commercial requirements 110 of the printer's art. Several arrangements of body may be used. For example, the

body members may be similar to those shown at 30 in Figs. 1, 2, 5, and 6, in which the width of the body is made a certain arbitrary size, and the thickness of the body 5 is that common to standard type, having the same size of face character. When type of this character is set up as illustrated in Fig. 1 the spacing of the vertical figures is exactly that which would be expected from 10 the size of the body, this giving the smallest spacing of lines which can be produced with size of face character used. If it is desired to use this size of face character between lines a greater distance apart, spacers such 15 as those illustrated at 31 in Figs. 5 and 6 are used. These spacers may be of any standard thickness and they enable any size of face character to be used with any line spacing greater than the thickness of the 20 type members 30. In common practice the printer has a font of type members such as those shown at 30, and a varied assortment of spacers 31, by means of which he can set up a type assembly such as that shown in 25 Fig. 5, for certain standard ruling spacing. He then adopts these spacings as standard, using them whenever possible so that a few set up assemblies will take care of the greater portion of his work. Type members 30 such as those shown at 32 may also be used in which the thickness of the body is greater than the height of the face characters so 35 wide spacings may be produced using a narrow face character without use of spacers.

35 In Figs. 2, 5 and 6 face figures, consisting of a single digit located in the center of the body member, are shown. It is often necessary to use figures having two digits in which case the form of type member illustrated in Figs. 3 and 4 may be used to advantage. In the form illustrated in these 40 figures right hand members 33, and left hand members 34, are provided, each of these members consisting of a body one-half 45 as large as the body 30, having a single side string groove 35, and having face characters 36 placed adjacent to the straight sides 37 which are opposite the sides having the side string grooves 35. The members 33 and 34 50 are assembled as shown in Fig. 3 to produce figures having two digits. When so assembled they are equivalent to the members 30 in so far as tying up with these members or 55 with spacers is concerned.

55 With all these forms of type members the underlying object is to produce type members which can be set up in a certain order, and which can be tied up to form a unit, this unit readily locking up in the form 60 with the various forms of standard furniture. For the purpose of so tying up the type members I use the string 40, this string passing through the side grooves 22 of the

single digit type members, or through the side grooves 35 illustrated in Figs. 3 and 4. 65 It is necessary, however, if the assembled unit is to lock up in the form that there be no projections on the end of the unit, and for this purpose I provide end grooves 41, 70 these end grooves extending across the end of certain of the type members, connecting the side grooves 22 as shown in the drawings. The end grooves 41 may be formed on the type members themselves as is the case in the member 32 illustrated in Fig. 2, 75 or a separate end spacing block 42 may be provided as illustrated in Figs. 2, 5 and 6. By the use of the end spacing groove 41 it is possible to pass the string several times completely around the assembled unit, and to 80 have the string well below the surface of the type so that the unit may be assembled with other type, or with printer's furniture without the string 40 interfering therewith. For the purpose of assisting in the composition 85 I provide small grooves 50 along one edge of the single digit type members, and spaces, and small grooves 51 along the side of the double digit type members illustrated in Figs. 3 and 4. 90

The method of operation of the invention will be evident from the foregoing description. The type members are assembled as shown in Fig. 1, being tied up with a string 40. When so assembled they can be moved 95 around without danger of any of them falling out or becoming misplaced, and they readily lock up in the form with standard type, or with standard printer's furniture. If wider spacing is desired the spacers 30 100 are used. If the numbers run beyond one digit the double digit members 33 and 34 may be used, or type members having double digits cast thereon similar in form to the members 30 or 32 may be used. 105

I claim as my invention:—

1. A type member comprising a flat body having side string grooves on either edge thereof, and having a numeral figure on the top thereof said numeral figure having its vertical axis parallel with edges having said grooves, said flat body having an edge string groove on one end thereof said edge string groove registering at either end with said side string groove. 110

2. A type member comprising a flat body member having side string grooves at the same height on either side thereof, and a numeral figure on the top of said body, said numeral figure being arranged with its vertical axis parallel to said sides. 120

In testimony whereof, I have hereunto set my hand at Los Angeles, California, this 25th day of September, 1915.

WILLIAM H. SMITH.
